UNITED STATES PATENT OFFICE.

WILLIAM H. DENNING, OF SOUTH TOTTENHAM, LONDON, ENGLAND, ASSIGNOR TO UNION TYPEWRITER COMPANY, OF JERSEY CITY, NEW JERSEY, A CORPORATION OF NEW JERSEY.

TYPE-WRITING MACHINE.

No. 914,121.

Specification of Letters Patent.

Patented March 2, 1909.

Application filed December 11, 1906. Serial No. 347,278.

To all whom it may concern:

Be it known that I, WILLIAM H. DENNING, a subject of the King of Great Britain, and resident of South Tottenham, London, England, have invented certain new and useful Improvements in Type-Writing Machines, of which the following is a specification.

My invention relates to typewriting machines and more particularly to tabulating mechanism and has for its object the provision of means whereby numbers or sets of numerals, for instance, may be differently pointed off or punctuated according to the character of the work to be written with the aid of the tabulating mechanism.

To the above and other ends which will be hereinafter described, my invention consists of the features of construction, arrangements of parts and combinations of devices to be described in the following specification and set forth in the accompanying claims.

In the drawings wherein like reference characters indicate corresponding parts in the various views—Figure 1 is a vertical, front to rear, central sectional view of a sufficient number of parts of a type-writing machine to illustrate my invention in its application thereto. Fig. 2 is a detail fragmentary vertical sectional view showing one of the denominational stops, an associated spacing block and means for mounting the latter. Fig. 3 is a detail perspective view of a portion of the carriage feed mechanism. Fig. 4 is a detail vertical sectional view showing a portion of the carriage feed mechanism. Fig. 5 is a detail top plan view of the machine with parts broken away. Fig. 6 is a rear elevation of the machine with parts broken away. Fig. 7 is an enlarged detail horizontal sectional view of a portion of the tabulating mechanism, the view being taken on the line $x-x$ of Fig. 6 and looking in the direction of the arrow at said line. Fig. 8 is a detail perspective view of a justifying device which operates with the denominational stop actuating levers. Fig. 9 is a detail top plan view of one of the spacing devices; the actuating lever with which it is adapted to coöperate being shown in section, the section being taken on the line $y-y$ of Fig. 6 and looking in the direction of the arrow at said line.

I have shown my invention applied to a No. 10 Yost typewriting machine and in connection with tabulating mechanism resembling that which is known as the Gorin

tabulator, though it should be understood that the invention may be employed in various styles of typewriting machines and in connection with different forms of tabulating mechanism.

In tabulator work it is often necessary or desirable to point off or punctuate differently according to the character of work to be produced. In some cases it may be necessary or convenient to write the numerals with the aid of the tabulator thus:—1234567890, assuming the tabulator is a ten key or ten stop tabulator or one capable of writing billions. Then, again, it may be necessary or desirable to point off the number thus:—1,234,567,890. In writing sterling money it may be convenient or desirable to point off the numbers so that pounds, shillings and pence will be properly divided thus:—

£	s.	d.
100,000	19	10

or thus:—

£	s.	d.
100,000	19	10

or thus:—

£	s.	d.
100,000	19	10

Heretofore when it was deemed necessary or desirable in, say, ten key or ten stop tabulators to point off thus:—1,234,567,890 it was necessary to change the index at the tabulator keys accordingly and to employ a tabulator key for each comma, punctuation mark, or space employed in pointing off the number. In the last example given it would be necessary to use three keys or stops for the commas between the numerals 1 and 2, 4 and 5 and 7 and 8 and one for the decimal point, so that even assuming that this could be done the scope of the tabulator would be reduced four stops. As a matter of fact, however, the operator could not in a ten key tabulator write a number higher than 9,999,999, instead of 999999999 where the commas and decimal point or spaces required for punctuation are not employed. By my present invention the pointing off of the numbers may be effected in any desired manner without reducing the capacity of the machine and the spacing required for punctuating may be effected by the tabulating mechanism itself. If, for instance, the invention is applied to a typewriting machine having a tabulator which employs ten tabulator keys or ten denominational stops, then

ten numerals may be written with the aid of the tabulator and spaced according to the desire of the operator as will clearly appear from the following description.

5 The foregoing illustrations of punctuation or spacing are merely taken as examples and it should be understood that the invention is capable of various uses and for effecting spacing of widely different varieties.

10 In the drawings, the frame of the machine comprises a base 1, corner posts 2 and a type ring or top plate 3. Each type bar comprises a type bar proper 4, a guide link 5 and a driver 6, the driver being pivoted at 7 to the type bar and the type bar being pivoted at 8 to a guide link. Each driver is pivoted on a circular pivot wire 9 and is connected at 10 to an upright link 11 pivoted at 12 to an angular lever 13 pivotally connected at 14 to a draw link 15, the forward end of which is pivoted at 16 to a device 17 pivoted on a fixed rod 18 supported in the base of the machine. The device 17 has a curved rearwardly extending arm 19 on which a key stem 20 is pivoted at 21. A guide link 22 is pivoted at one end to a fixed pivot 23 and at its opposite end to the key stem at 24. Each key stem is provided with a finger piece or button 25 by which the associate type action 30 may be operated. The types normally rest against an inking pad 26 and a depression of a key 25 causes the associated type bar to be moved upwardly to the printing point. In the upward movement of the type bar its 35 associated guide link 5 contacts with a universal ring or frame 27 which is connected to a depending stem or spindle 28. The lower end of the spindle is operatively connected to a forwardly extending arm 29 of a dog rocker 40 pivoted at 30 and carrying feed dogs 31 which coöperate with an escapement wheel 32. The escapement wheel is operatively connected to the carriage in the following manner.

45 Upon reference to Figs. 3 and 4 it will be seen that the teeth 33 of a clutch device 34 are adapted to engage corresponding clutch teeth on a member 35 which carries the escapement wheel 32. A spring 36 bears down 50 on the clutch device 34 and normally maintains it in engagement with the clutch teeth on the member 35. The clutch device 34 is connected to a vertically disposed hollow spindle or shaft 37 provided with a flange or collar 38 and a pinion 39. The pinion 39 meshes with a feed rack 40 secured by screws 41 to a guide bar or carriage truck. This guide bar is grooved on the front and rear sides thereof for coöperation with anti-friction balls 43 which are also received in fixed grooved guide rails 44. A platen frame 45 carries a cylindrical platen 46 which is journaled in the end bars of the platen frame. This platen frame is pivotally connected to 60 the carriage truck or bar 42 and carries an

anti-friction roller 47 which is supported on a fixed rail 48. The mechanisms thus far described constitute portions of the well-known No. 10 Yost machine and a further description thereof is deemed unnecessary.

70 A tabulator frame 49 is secured to the top plate or type ring of the machine by screws 50 and is secured to the base of the machine by screws 51. This frame comprises side members 49^a which support a fixed spindle 75 or pivot 52 on which upright actuating levers 53 are supported and adapted to turn. These levers carry denominational stops, separately indicated in Figs. 5 and 6 by the reference numerals 54^a to 54ⁱ, and which are or may be 80 formed integral with their associate actuating levers 53. The levers 53 are slidable along the pivot rod 52 so that an adjustment of both the levers and denominational stops may be effected as will hereinafter more 85 clearly appear. The lower end of each actuating lever 53 is pivotally connected at 55 to a push rod 56 that extends forwardly to the front of the machine where it passes through a bearing opening in a supporting piece 57 90 secured to the base of the machine. Each of the push rods 56 is provided with a finger piece or button 58 and an adjustable collar 59 to which one end of a restoring spring 60 is connected, the opposite end of said spring 95 being connected to a pin 61 carried by the supporting piece 57. Upwardly and rearwardly extending bracket arms 62 are secured to the carriage truck or bar 42 and support a toothed column stop rod 63 which 100 carries bifurcated column stops 64 which may be adjusted to any desired point along the column stop rod or bar to determine the columnar position of arrest of the carriage.

105 A universal bar 65, which constitutes a portion of the carriage releasing mechanism of the tabulating mechanism, extends in front of the upper arms of the upright levers 53 as shown in Fig. 1. This bar is connected to depending arms 66 secured to a rock shaft 110 67 supported in bearings in the side members 49^a of the tabulator frame 49. A forwardly extending arm 68 is also secured to the rock shaft 67 and is bifurcated at its forward end to embrace loosely the hollow shaft 37 and 115 to coöperate with the collar 38 carried thereby. A rearward movement of one of the finger buttons 58 effects a forward movement of one of the denomination stops, thereby bringing it into the path of the column 120 stop 64. This same movement causes the upper arm of the actuating lever 53 to move the bar 65 towards the front of the machine, thus effecting an upward movement of the hollow spindle or shaft 37 which results in 125 disengaging the clutch members and freeing the carriage from control of the escapement mechanism without, however, disengaging the pinion 39 from its coöperating feed rack 130 40. The carriage being thus released moves

from right to left under the influence of the usual spring drum (not shown) until it is arrested by the contact of one of the column stops with the projected denominational stop.

5 From an inspection of Fig. 5 it will be observed that the side members 49^a of the frame 49 which receive the denominational stops 54^a, 54^b, 54^c, 54^d, 54^e, 54^f, 54^g, 54^h, 54ⁱ, 54^j, are situated a greater distance apart than the 10 combined width of the series of ten denominational stops. The excess space in the present instance corresponds to the thickness of seven of the denominational stops, although this distance may be made greater or less.

15 The manner of mounting the denominational stops and the actuating levers 53 of which they form parts is such that the levers and denominational stops may be moved or adjusted laterally or in the direction of the 20 travel of the carriage when desired to different working positions, as hereinbefore pointed out. The spaces between the denominational stops, or at the outer side thereof, may be occupied by what I have termed spacing 25 blocks 69, seven of such blocks being shown in the present instance and each corresponding in thickness to the thickness of a denominational stop, which corresponds to a letter space movement of the carriage. Each of 30 the spacing blocks 69 (see Fig. 2) is formed with a notched portion 70 by which the stop may be mounted and held in place on a rear cross bar 71 which unites the side members 49^a of the tabulator frame. A detachable 35 locking member 72 (see Figs. 2 and 5) extends across the top of the series of denominational stops and spacing blocks and is provided with downwardly bent ends which are received in openings 73 in the upper ends of 40 the side members 49^a of the tabulator frame. By removing this locking member 72 or displacing one end thereof from its slot and turning it forwardly out of the path of the 45 spacing blocks they may be removed and shifted as desired. In the specific arrangement shown it may be assumed that the spacing blocks are arranged so as to separate the denominational stops in order that pounds, shillings and pence, for instance, may be 50 written as thus:

$\mathcal{L} \quad s. \quad d.$

100,000 19 10

or thus:

$\mathcal{L} \quad s. \quad d.$

100,000 19 10

55 In order that the lower ends of the actuating levers 53 may be spaced according to the spacing between the denominational stops, I have provided means which are best shown 60 in Figs. 6, 7, 8 and 9. All levers 53, except the right-hand one as viewed from the rear of the machine, are each provided at the rear side with a notch 74 by which a spacing block 75 may be applied to the rod. Each of these 65 spacing blocks has a cut-out portion 76 with three teeth 77 on the opposite side walls of the cut-out, thus providing three sets of openings 78, 78^a and 78^b between the teeth, though a greater or less number of such teeth and spaces may be provided. The width of 70 each opening corresponds substantially to the thickness of one of the levers 53, and the width of the notch 74 in the lever corresponds substantially to the thickness of the spacing block 75. The distance between two 75 adjacent notches 78, 78^a and 78^b corresponds substantially to a letter space movement of the carriage so that each spacing block 75 may be adjusted on an actuating lever 53 and a contact edge 79 on the spacing 80 block may be moved one, two or three letter space distances nearer to or farther from the lever 53 on which the spacing block 75 is mounted. Each of the levers 53 is provided near its lower end with an off-set, flange or 85 support 80 on which an associated spacing block 75 is adapted to rest as shown in Fig. 6. Each spacing block 75 may be readily disconnected from or connected to one of the levers 53 by bringing the cut-out 76 therein into 90 register with the notch 74 in the lever to which the spacing block is to be applied as indicated in Fig. 9. The spacing block may then be moved to the left in Fig. 9 so that one or more of the teeth 77 at one side of the cut-out 76 will pass through the notch 74 until the set of openings 78, 78^a or 78^b with which the lever is to co-operate are in register with the body of the lever. The spacing block may then be permitted to drop down to a 100 position such as shown in Fig. 6 where the spacing block will be supported on the laterally extending flange or support 80 and will engage the body portion of the associated lever and the edge 79 on the spacing block 105 will contact with the next adjacent lever 53 to the right as seen in Fig. 6. From an inspection of this figure it will be seen that the three denominational stops 54^a, 54^b and 54^c at the left are contiguous, whereas one spacing 110 block 69 is inserted between the third and fourth denominational stops 54^c and 54^d respectively. It requires therefore that a similar spacing be provided between the lower ends of the stop levers 53, hence a spacing 115 block 75 is inserted in place in the manner hereinbefore described on the third actuating lever 53 from the left in Fig. 6, so that the innermost notches 78^b in the spacing block will engage the lever, thus providing a single 120 additional letter space between the lower ends of the third and fourth actuating levers from the left in Fig. 6. At this time the contact edge 79 of the spacing block 75 is maintained in contact with the side of the actuating lever which is the fourth from the left as seen in Fig. 6. This spacing of the lower ends of those levers 53 which are associated with denominational stops to each side of the left-hand spacing block 69 corresponds 125 130

therefore to the spacing between the denominational stops effected with the aid of the left-hand block 69. The three denominational stops 54^d, 54^e and 54^f are contiguous and the denominational stops 54^f and 54^g are separated by three spacing blocks 69. The actuating levers of the three contiguous stops 54^d, 54^e and 54^f need no spacing at their lower ends other than that afforded by the projections 80. It is desirable, however, that a distance corresponding to three letter space movements of the carriage, or to the width of three of the spacing blocks 69, be provided between the lower ends of the actuating levers of the denominational stops 54^f and 54^g. This is effected by adjusting one of the spacing blocks 75 so that the spaces 78 therein co-act with the lever on which the spacing block is supported, thus affording a requisite amount of space between the actuating levers associated with the stops 54^f and 54^g. In a like manner three spacing blocks 69 are provided between the denominational stops 54^h and 54ⁱ and a like adjustment of one of the spacing blocks 75 is provided to properly separate the lower ends of the actuating levers for these denominational stops.

In order to maintain the lower ends of the actuating levers against lateral displacement in the positions to which they are adjusted, I provide a so-called compensating device designated as a whole by the reference numeral 81 and which is shown in detail in Fig. 8. This device comprises a spacing member 35 or contact device, the body portion of which is bifurcated at 82 to straddle a supporting bar 83 which extends from one side member 49^a of the tabulator supporting frame to the other and is secured at the front portion 40 thereof in front of the levers 53. This supporting bar 83 is formed with serrations or teeth 84 for coöperation with the engaging end 85 of a spring-pressed locking member 86 pivoted at 87 to the compensating device 81 and working in a slot in the lower portion thereof. This locking member on the compensating device is adapted to engage with the teeth of the bar 83, whereas the body portion of the compensating device contacts 45 with the left-hand actuating lever as viewed in Fig. 6 and maintains the levers against lateral movement in one direction when they are properly spaced apart, the projection 80 on the right-hand lever contacting with one 50 of the side members 49^a. Thus, for instance, if the operator should desire to remove all of the spacing blocks 69 and 75 from between the denominational stops and levers 53 respectively, in order to maintain all of the 55 denominational stops contiguous one to another, then, all of the stops and levers should be moved to the extreme right as seen in Fig. 6 and the device 81 should be moved to the right in order to compensate for the 60 space provided by the removal of the stops 65

75, and so that the projections 80 on the lower ends of the actuating levers contact with each other and with the right-hand side member 49^a. The spacing blocks 69 removed from between the denominational 70 stops should, in this event, be inserted to the left of the series of denominational stops so as to compensate for the space provided by the removal of the spacing blocks 69 from between the denominational stops. 75

While I have shown the construction arranged for seven spacing blocks 69 and have shown each of the spacing blocks arranged for an adjustment of from one to three spaces, it will be understood that the arrangement may be such that a greater or less number of blocks 69 may be employed and that the blocks 75 may have a greater or less number of teeth 77 to give a greater or less variation in the adjustment of the 85 blocks 75.

It is believed that the operation of the mechanism will be understood from the foregoing description.

Various changes in the construction may 90 be made without departing from my invention which, in its broad aspect, contemplates a provision of means for regulating the parts so as to vary at will the extent of spacing between adjacent denominational 95 positions of arrest of the carriage through the control of the tabulating mechanism.

What I claim as new and desire to secure by Letters Patent, is:—

1. In a typewriting machine and tabulating mechanism, the combination of a plurality of adjustable denominational stops, and detachable spacing blocks that may be interposed between the denominational stops. 100

2. In a typewriting machine and tabulating mechanism, the combination of a plurality of adjustable denominational stops, a plurality of adjustable key actuated levers for actuating said stops, detachable spacing blocks that may be interposed between said 110 stops, and detachable spacing blocks that may be interposed between said levers. 105

3. In a typewriting machine and tabulating mechanism, the combination of a stop frame, a plurality of denominational stops 115 mounted in said frame and adjustable therein to different positions relatively to one another and in the direction of the travel of the carriage in order to vary the spacing between the stops for changing the punctuation that may be employed, detachable means for preventing a lateral displacement of the stops from the positions to which they are adjusted, actuating devices for said stops also mounted for lateral adjustment in 120 said frame according to the adjustment of said stops, and separate detachable means for preventing a lateral displacement of said actuating devices from the positions to which they may be adjusted. 125

4. In a typewriting machine and tabulating mechanism, the combination of a carriage, a plurality of column stops carried by the carriage, a plurality of co-acting 65
5 nominal stops carried by the frame of the machine; the column and denominational stops receiving a relative movement transversely of the travel of the carriage to bring them into position for coöperation, 10 and the denominational stops being relatively adjustable in the direction of the travel of the carriage to different working positions, and detachable spacing blocks that are 15 adapted to be interposed between said denominational stops to prevent a lateral displacement of the stops from the positions to which they have been adjusted. 20
5. The combination with a typewriting machine and tabulating mechanism including 25 denominational stops, of means for actuating said denominational stops, means for adjusting the denominational stops so as to change the punctuation, and separate means for adjusting the actuating means according 30 to the adjustment of the denominational stops. 35
6. In a typewriting machine and tabulating mechanism, the combination of a plurality of adjustable denominational stops, adjustable actuating means therefor, detachable spacing blocks that may be interposed between the denominational stops, and detachable spacing blocks that may be interposed between the actuating means for said denominational stops. 40
7. In a typewriting machine and tabulating mechanism, the combination of a plurality of adjustable denominational stops, adjustable actuating means therefor, detachable spacing blocks that may be interposed between the denominational stops, and detachable and adjustable spacing blocks that 45 may be interposed between the actuating members for the denominational stops in order to adjust said actuating means according to the adjustment of the denominational stops. 50
8. In a typewriting machine and tabulating mechanism, the combination of a series of denominational stops, means for adjusting the relation between said stops, levers for actuating said stops, and toothed spacing blocks detachable from and adjustable on said levers to space the levers according to the spacing of the denominational stops. 55
9. In a typewriting machine and tabulating mechanism, the combination of a series of denominational stops; means for adjusting the relation between said stops; levers 60 for actuating said stops, said levers having notches therein; and toothed spacing blocks, portions of which pass through said notches whereby the spacing blocks are rendered detachable from and adjustable on said levers to space the levers according to the spacing of the denominational stops. 65
10. In a typewriting machine and tabulating mechanism, the combination of a series of denominational stops, means for adjusting the relation between said stops; levers for 70 actuating said stops, said levers being adjustable in the direction of the travel of the carriage and provided with laterally extending projections for maintaining them spaced apart; and spacing devices detachable from 75 and adjustable on said levers, said spacing devices being adapted to project different distances beyond the contact edges of the laterally extending projections with which they are associated. 80
11. In a typewriting machine and tabulating mechanism, the combination of a series of denominational stops; means for adjusting the relation between said stops; levers for actuating said stops, said levers being adjustable in the direction of the travel of the carriage and provided with laterally extending projections for maintaining them spaced apart; spacing devices detachable from and 85 adjustable on said levers, said spacing devices being adapted to project different distances beyond the contact edges of the laterally extending projections with which they are associated; and an adjustable compensating device coöoperative with one of the 90 outside levers. 95
12. In a typewriting machine, the combination of a series of denominational stops adjustable in the direction of the travel of the carriage, a bar, and a series of detachable 100 spacing blocks each adapted to be inserted between adjacent denominational stops to maintain them against lateral displacement in the positions to which they have been adjusted, said blocks having engaging means 105 coöoperative with said bar for supporting the blocks in place. 110
13. In a typewriting machine, the combination of a series of denominational stops adjustable in the direction of the travel of the carriage, a bar, a series of detachable 115 spacing blocks each adapted to be inserted between adjacent denominational stops to maintain them against lateral displacement in the positions to which they have been adjusted, said blocks having engaging means coöoperative with said bar for supporting the blocks in place, and a movable retaining device coöoperative with said blocks to prevent 120 an accidental displacement of the blocks from between said denominational stops. 125
14. In a typewriting machine, the combination of a series of denominational stops adjustable in the direction of the travel of the carriage, a series of actuating levers each formed as a part of a denominational stop, detachable and interchangeable blocks for spacing said denominational stops apart, 130

and detachable and interchangeable blocks for spacing said levers apart.

15. In a typewriting machine, the combination of a series of denominational stops, 5 means for effecting a relative adjustment between said stops in the direction of the travel of the carriage, actuating levers for said stops, said levers having notches therein, and spacing blocks each having a cut-out 10 therein with teeth on each side of the cut out,

whereby the spacing blocks may be detached from and adjusted on said levers.

Signed at South Tottenham, London, England, this 29th day of November, A. D. 1906.

WILLIAM H. DENNING.
